CLOTHES-WASHING MACHINE WITH
DIAPHRAGM SQUEEZER EXTRACTOR

George P. Castner, Webster City, Iowa

Application November 1, 1949, Serial No. 124,869

5 Claims. (Cl. 68—21)

1

The present invention relates to clothes washing machines, and more particularly to improved clothes washing machines of the character of that disclosed in the copending application of George P. Castner, Serial No. 110,570, filed August 16, 1949, and now abandoned.

Fundamentally the clothes washing machine disclosed in the Castner application mentioned comprises an upstanding tubular housing formed of sheet metal, a top wall supported in the upper end of the housing, and a tub arranged in the upper portion of the housing and secured directly to the top wall, the top wall and the tub having registering top openings respectively formed therein to accommodate placement and removal of the clothes with respect to the tub. Also, the machine comprises washing mechanism including a substantially disk-like dasher arranged in an upstanding position in the tub adjacent to a side wall thereof and mounted for operation directly on the side wall. An electric drive motor is arranged below the tub and is supported directly thereby, and a drive connection is provided between the motor and the dasher. Further, a cover is mounted on the top wall for movements between open and closed positions with respect to the top openings mentioned. Finally, a hand operated wringer is mounted on the underside of the cover and is movable therewith through the registering top openings between operative and storage positions, the wringer being disposed above the top wall in its operative position when the cover occupies its open position, and being disposed within the tub in its storage position when the cover occupies its closed position.

While this machine is highly satisfactory in operation and economical to manufacture, the necessary handling of the clothes and the manual operation of the wringer are somewhat inconvenient.

Accordingly, it is a general object of the present invention to provide a clothes washing machine of the character described that incorporates an improved power operated water extracting mechanism, whereby, after a washing operation has been performed upon the clothes in the tub, a water extracting operation may be performed upon the clothes in the tub, all without handling of the clothes, and entirely by the power operated washing and water extracting mechanisms.

Another object of the invention is to provide in a clothes washing machine, an improved water extracting mechanism of the squeeze type that cooperates with a wall of the tub to express the water from the clothes contained in the tub.

2

Another object of the invention is to provide in a clothes washing machine, a water extracting mechanism of the squeeze type that is of improved construction and arrangement so that the operation thereof to express the water from the clothes is substantially independent of the load of the clothes contained in the tub.

A further object of the invention is to provide in a clothes washing machine including washing mechanism and water extracting mechanism of the squeeze type, an improved control arrangement for the mechanisms that is so organized that simultaneous operations thereof are prevented in order positively to eliminate the possibility of damage to the clothes by operation of the washing mechanism during operation of the water extracting mechanism.

A further object of the invention is to provide in a clothes washing machine, a tub and squeeze bag of improved construction and arrangement that accommodate extraction of water from clothes in the tub after they have been washed therein.

Further features of the invention pertain to the particular arrangement of the elements of the clothes washing machine and of the elements of the control system therefor, whereby the above-outlined and additional operating features thereof are attained.

The invention, both as to its organization and principle of operation, together with further objects and advantages thereof, will best be understood by reference to the following specification taken in connection with the accompanying drawings, in which Figure 1 is a plan view of a clothes washing machine embodying the present invention; Fig. 2 is a side elevational view of the machine shown in Fig. 1; Fig. 3 is a front elevational view of the machine shown in Figs. 1 and 2; Fig. 4 is an enlarged vertical sectional view of the machine, taken transversely of the tub in the direction of the arrows along the line 4—4 in Fig. 3; Fig. 5 is an enlarged fragmentary vertical sectional view of the upper portion of the machine, taken transversely of the tube in the direction of the arrows along the line 5—5 in Fig. 4; Fig. 6 is an electrical diagram of the circuit control network for the machine shown in Figs. 1 to 5, inclusive; and Fig. 7 is an enlarged fragmentary vertical sectional view of the upper rear portion of a modified form of the clothes washing machine embodying the present invention, this view being taken longitudinally of the tub and corresponding to Fig. 4 and illustrating an alternative construction and arrangement of

the squeeze diaphragm or bag incorporated in the machine.

Referring now to Figs. 1 to 5, inclusive, of the drawings, there is illustrated a clothes washing machine 10 of the general character of that disclosed in the previously mentioned Castner application and embodying the features of the present invention. The machine 10 comprises an upstanding base 11 carrying on the upper portion thereof an upstanding tub 12. The base 11 comprises front and rear walls 13 and 14, side walls 15 and 16 and a bottom wall 17. The bottom wall 17 has an enlarged centrally disposed opening 18 formed therein, and is provided adjacent to the corners thereof with downwardly depressed feet 19 adapted to engage a supporting floor, or the like. The top of the base 11 is open in order that the upper portion thereof may receive and enclose the lower portion of the tub 12 carried thereby as explained more fully hereinafter. The tub 12 comprises cooperating front and rear cup-shaped sections 20 and 21 secured together in facing liquid-tight relation by cooperating inner and outer rings or bands 22 and 23 secured together by a series of screws 24. The front section 20 comprises an upstanding front wall 25 and a connected rearwardly directed tubular side wall 26; while the rear section 21 comprises an upstanding rear wall 27 and a connected forwardly directed tubular side wall 28. The tubular side wall 26 comprises a laterally extending substantially flat forwardly and downwardly sloping top wall 29, two downwardly directed side walls 30 and 31 and an arcuate bottom wall 32; while the tubular side wall 28 comprises a laterally extending substantially flat horizontal top wall 33, two downwardly directed side walls 34 and 35 and an arcuate bottom wall 36. Accordingly, the rear edges or ends of the walls 29, 30, 31 and 32 of the front section 20 and the front edges or ends of the walls 33, 34, 35 and 36 of the rear section 21 are secured together in liquid-tight relation by the rings 22 and 23.

The bottom walls 32 and 36 respectively carry two laterally extending and longitudinally spaced-apart brackets 37 and 38 that may be secured thereto by welding, or the like, which brackets 37 and 38 are suitably secured to a longitudinally extending supporting plate 39 arranged below the tub 12. The opposite ends of the supporting plate 39 are carried upon two laterally extending substantially L-shaped members 40 and 41 respectively secured to the front wall 13 and to the rear wall 14 by two series of screws 42 and 43. The members 40 and 41 are arranged within the base 11 and receive the opposite ends of the supporting plate 39 as noted above, whereby the supporting plate 39, as well as the tub 12, are supported in position within the upper portion of the base 11. Thus, the lower portion of the tub 12 is enclosed within the upper portion of the base 11 and cooperates with the bottom wall 17 to define a machinery space 44 in the lower portion of the base 11. The upper edges of the front and rear walls 13 and 14 are inwardly curved as indicated at 45 and 46 in order to engage the respective front and rear walls 25 and 27; and similarly the upper edges of the side walls 15 and 16 are inwardly curved and folded back upon themselves as indicated at 47 and 48 in order to engage the opposite sides of the bottom walls 32 and 36.

A substantially laterally extending rectangular opening 49 is formed substantially centrally in the top wall 29 of the front section 20 in order to render the interior of the tub 12 accessible from the exterior. The opening 49 is surrounded by an inwardly directed marginal throat 50 and is provided with a door 51 movable between open and closed positions with respect thereto. The door 51 includes inner and outer sheets 52 and 53 suitably secured together and mounted upon two laterally spaced-apart hinge mechanisms 54 of any suitable type. Also, the door 51 comprises latch mechanism indicated generally at 55 and comprising a rotatably mounted handle 56 that controls the sliding movements of two associated latch elements 57 that cooperate with the throat 50 in order securely to latch the door 51 in its closed position. It will be understood that the door 51 is normally latched in its closed position and that it is necessary first to rotate the handle 56 in order to release the latch mechanism 55 before the door 51 may be moved from its closed position into its open position. Subsequently, when the door 51 is moved from its open position back into its closed position the latch mechanism 55 operates automatically to latch the door 51 in its closed position.

Arranged within the tub 12 is an upstanding flexible substantially cup-shaped diaphragm 58 formed of rubber, or the like, and including what may be termed an end wall 59 and a flange wall 60, the marginal edge or perimeter of the flange wall 60 being clamped between the rings 22 and 23. The diaphragm 58 has a normal concave position in which it conforms substantially to the interior surface of the rear section 21 of the tub 12. In its concave position the diaphragm 58 cooperates with the front section 20 to define a compartment 61 within the tub 12, and cooperates with the rear section 21 to define a chamber 62 within the tub 12, the compartment 61 and the chamber 62 being separated from each other by the diaphragm 58. The compartment 61 is accessible from the exterior through the opening 49 when the door 51 occupies its open position and is adapted to receive wash liquid and clothes to be washed.

Also arranged within the compartment 61 adjacent to and rearwardly of the front wall 25 is an upstanding perforated wall or plate 63, the configuration of the plate 63 conforming substantially to that of the front wall 25. The plate 63 may be formed of one-piece die cast construction or pressed directly from a fairly heavy gauge of stainless steel, or the like, the plate 63 being perforated by the provision of a number of holes 64 therein. Further, the position of the plate 63 spaced rearwardly with respect to the front wall 25 is maintained by a series of spaced-apart stanchions 65 disposed therebetween, the front ends of the stanchions 65 being suitably secured to the adjacent face of the front wall 25 and the rear ends of the stanchions 65 being suitably secured in aligned openings provided in the plate 63. Accordingly, the upstanding front wall 25 and the upstanding plate 63 define an upstanding space 66 therebetween, with which space 66 a downwardly extending drain connection 67 formed in the bottom wall 32 communicates.

A forwardly directed substantially annular emboss 68 is formed in the upper central portion of the plate 63 in order to provide a substantially circular recess 69 surrounded thereby, the centers of the emboss 68 and of the recess 69 being substantially coincident with each other and with

the arc of the bottom walls 32 and 38 of the respective sections 20 and 21 of the tub 12. A disk-like dasher plate 70 is arranged within the recess 69 and mounted upon the rear end of an operating shaft 71 that extends through aligned openings respectively formed in the front wall 25 and in the plate 63. More particularly, the operating shaft 71 is supported and journaled for rotation substantially along the longitudinal axis of the tub 12 in bearing structure including complementary sections 72 and 73 respectively disposed interiorly and exteriorly of the front wall 25 adjacent to the center of the emboss 68, whereby the sections 72 and 73 provide a liquid-tight joint surrounding the opening provided in the front wall 25 and preventing the escape from the tub 12 of wash liquid along the operating shaft 71. The front end of the operating shaft 71 carries a pulley 74 rigidly secured thereto, whereby the operating shaft 71 and the dasher plate 70 may be rotated unidirectionally.

As best shown in Fig. 5, the dasher plate 70 is rotated unidirectionally in the clockwise direction, as viewed from the front face thereof, and carries on its front face three relatively shallow outstanding vanes 75, 76 and 77, the vane 75 being disposed on one side of the center of rotation of the dasher plate 70 and the vanes 76 and 77 being disposed on the other side of the center of rotation of the dasher plate 70 and in radial spaced-apart relation with respect to each other. The vanes 75, 76 and 77 are removed from the center of rotation of the dasher plate 70 and extend in a crosswise to radial direction with respect to the center of rotation thereof, each of the vanes 75, 76 and 77 being tapered and provided with leading and trailing ends with respect to the direction of rotation of the dasher plate 70 so that the leading end of each vane is closer than the trailing end thereof to the front face of the dasher plate 70. For example, the leading ends of the vanes 75, 76 and 77 marked "L" may be in the plane of the front face of the dasher plate 70, while the trailing ends of the vanes marked "T" may be disposed outwardly therefrom, the taper being continuous between the ends "L" and "T." Also, a shallow recess 78 is provided in the front face of the dasher plate 70 between the vanes 76 and 77, this recess 78 assisting in the release of the clothes from the front face of the dasher plate 70 as explained more fully hereinafter. The central portion of the dasher plate 70 is provided with a forwardly directed boss 79 having a hole 80 therein that receives the rear end of the operating shaft 71 as previously noted. Also a substantially annular resilient element 81 formed of rubber, or the like, is suitably secured upon the peripheral edge of the dasher plate 70 in order to prevent working of the clothes contained in the tub 12 between the dasher plate 70 and the plate 63 and the consequent breakage of buttons, or the like, carried upon the clothes.

Arranged within the machinery space 44 provided in the base 11 is an electric motor 82 of any suitable type that is preferably operative by a commercial source of 110 volts 60 cycle A. C. supply, the base of the motor 82 being suitably secured to the supporting plate 39. The motor 82 includes a rotor, not shown, provided with an operating shaft 83 that projects from the opposite end bells thereof, the front and rear ends of the operating shaft 83 respectively terminating in two solenoid-controlled clutch mechanisms 84 and 85, also suitably carried by the supporting

plate 39. Also, a stub shaft 86 is suitably journaled in a bearing hanger 87, that is also carried by the supporting plate 39, the rear end of the stub shaft 86 terminating in the clutch mechanism 84 and the front end of the stub shaft 86 having a pulley 88 rigidly secured thereto. The front end of the stub shaft 86 extends through an opening 89 formed in the front wall 13, whereby the pulley 88 is disposed forwardly of the front wall 13 and below and in alignment with the pulley 74. The pulleys 74 and 88 are of the V-belt type and are interconnected by a V-belt drive connection 90. The pulleys 74 and 88 and the V-belt 90 are enclosed in a hood 91 removably secured to the front walls 25 and 13 by an arrangement including a plurality of screws 92. The screws 92 extend through openings provided in the hood 91, the inner ends of the screws 92 being threaded in tapped holes provided in certain of the stanchions 65.

Also, two aligned stub shafts 93 and 94 are arranged within the machinery space 44, the front end of the stub shaft 93 terminating in the clutch mechanism 85 and the rear end of the stub shaft 94 being suitably journaled in a bearing hanger 95, that is carried by the supporting plate 39. The adjacent ends of the stub shafts 93 and 94 are operatively connected to the component elements of a fluid drive or coupling mechanism 96. For example, the rear end of the stub shaft 93 may be connected to the bladed element of the mechanism 96 and the front end of the stub shaft 94 may be connected to the casing, indicated at 97, of the mechanism 96, the casing 97 containing a suitable quantity of hydraulic medium, such, for example, as oil. A drain pump 98 surrounds the stub shaft 93 and is provided with a rotor, not shown, rigidly secured thereto; and a compression pump 99 surrounds the stub shaft 94 and is provided with a rotor, not shown, rigidly secured thereto.

Further, the mechanism 10 comprises a fluid inlet conduit 100 and a fluid outlet conduit 101 that are provided with respective coupling elements 102 and 103 permitting connection thereof to exterior plumbing, not shown. The inlet conduit 100 is normally connected via the coupling element 102 and a suitable section of rubber hose, not shown, to a water tap provided in the laundry room; and the outlet conduit 101 is normally connected via the coupling element 103 and a suitable section of rubber hose, not shown, to a laundry tray or other drain plumbing in the laundry room. The drain pump 98 is provided with an inlet connection 104 that is connected by a suitable section of flexible hose 105 formed of rubber, or the like, to a solenoid-controlled drain valve V1 that is connected to the drain connection 67. Also, the drain pump 98 is provided with an outlet connection 106 that is connected directly to the outlet conduit 101. The compression pump 99 is provided with an inlet connection 107 that is connected directly to a substantially T-shaped section of conduit 108, and an outlet connection 109 that is connected directly to a substantially T-shaped section of conduit 110. The conduit 110 is connected via a solenoid-controlled valve V2 to a substantially T-shaped section of conduit 111; the inlet conduit 108 is connected to the conduit 108 by a solenoid-controlled valve V3; the conduit 108 is connected to the conduit 111 by a solenoid-controlled valve V4; and the outlet conduit 101 is connected to the conduit 110 by a solenoid-controlled valve V5. Further, a fixture 112 is secured within a de-

pression 113 formed in the lower portion of the bottom wall 36 and communicates between the chamber 62 and the conduit 111. Finally, a pressure-controlled limit switch LS also communicates with the conduit 111.

In the machine 10 the base 11 may be formed of sheet steel and of wrap-around construction; and likewise the hood 91 may be formed of sheet steel and of die-pressed construction. Preferably, the sections 20 and 21 of the tub 12, as well as the component elements of the door 51, are formed of corrosion resistant material, such, for example, as stainless steel. Finally, the base 11 and the hood 91 may be provided with an exterior finish of white enamel, or the like. The machine 10 is readily portable, and as a constructional example the tub 12 may have substantially the following dimensions. The distance between the rear wall 27 and the center of the ring 22 may be 7 inches; the distance between the center of the ring 22 and the front wall 25 may be 8 inches; and the plate 63 may be spaced 1 inch rearwardly of the front wall 25. The arc of the bottom walls 32 and 36 may be on a 9" radius, whereby the side walls 30-31 and 34-35 are spaced from each other 18 inches. Further, the side walls 34 and 35 may extend upwardly 11 inches above the center line of the operating shaft 71 to join the horizontal top wall 33; while the side walls 30 and 31 extend upwardly suitably above the center line of the operating shaft 71 to join the forwardly sloping top wall 29. Finally, the front portion of the top wall 29 may be disposed 1½ inches below the rear portion thereof to provide the forward slope noted.

For the purpose of controlling the washing mechanism, including the dasher plate 70, an electric control switch 120 of the manually operable two-position type is mounted within the upper left-hand side of the hood 91, the switch 120 being provided with a manually operable handle that is restrained in either one of its two operating positions when operated thereto. For the purpose of controlling the water extracting mechanism, including the diaphragm 58, an electric control switch 121 of the manually operable three-position type is mounted within the upper right-hand side of the hood 91, the switch 121 being provided with a manually operable handle that is restrained in any one of its three operating positions when operated thereto. The connection and arrangement of the electric control network of the various elements of the machine 10 will best be understood by reference to Fig. 6, wherein there are illustrated diagrammatically the elements mentioned. In the circuit network a commercial 60 cycle 110 volts A. C. source is employed, one conductor thereof being grounded in the machine 10 and indicated by the sign “-” and the other conductor thereof being ungrounded in the machine 10 and indicated by the sign “+.” The motor 82 may be of any suitable type, as previously noted; the solenoids of the clutches 84 and 85 are respectively indicated at 84' and 85'; the solenoids of the valves V1, V2, V3, V4 and V5 are respectively indicated at SV1, SV2, SV3, SV4 and SV5; and the limit switch of the pressure-controlled type is indicated at LS. The wash control switch 120 comprises six individual springs providing individual contacts 1 to 4, inclusive; and the diaphragm or bag control switch 121 comprises seven individual springs providing individual contacts 1' to 6', inclusive.

Considering now the operation of the machine 10 and assuming that the user wishes to wash a

given load of clothes, she first seizes the handle 56 and rotates it in order to unlatch the door 51, whereby the door 51 is then moved to its open position. The user then places the clothes with- 5 in the compartment 61 through the opening 49, fills the tub 12 with hot or warm water or liquid as required by the character of the fabrics to be washed, and then places an appropriate amount of detergent in the wash water contained in the tub 12. Normally, the wash water is placed in the tub 12 so that the head thereof rises somewhat above the upper portion of the annular emboss 68 completely submerging the dasher plate 70, the normal water level in the tub 12 being 10 indicated by the broken line 130. At this time the door 51 is returned to its closed position by the user, whereby it is automatically latched securely in place by the latch mechanism 55. The wash switch 120 is then operated from its “off” 15 position into its “on” position, whereby there is completed, at the contacts 2 thereof, a circuit for operating the motor 82; and there is completed, at the contacts 3 thereof, a circuit, including the contacts of the limit switch LS, for energizing 20 the solenoid 84' of the clutch mechanism 84. Also, at the contacts 1 and 4 of the wash switch 120, there are interrupted points in connections extending to the bag switch 121, thereby positively to render the bag switch 121 inoperative 25 to bring about control operations while the wash switch 120 comprises its “on” position. When the motor 82 is thus energized it operates, whereby the operating shaft 83 thereof is rotated in the 30 counterclockwise direction, as viewed from the front of the machine 10. When the solenoid 84' of the clutch mechanism 84 is thus energized the clutch plates, not shown, thereof are moved into clutched position, whereby the stub shaft 86 is rotated by the operating shaft 83 in the 35 counterclockwise direction. The rotating stub shaft 86 effects rotation of the associated pulley 88, whereby the pulley 74 is rotated through the v-belt 90 bringing about rotation of the operating shaft 71 and the dasher plate 70 in the counterclockwise direction, as viewed from the front of the machine 10. When the dasher plate 70 is thus rotated in the counterclockwise direction it moves and rearranges the clothes contained 40 in the compartment 61 formed in the tub 12 in a substantially circular upstanding path. Specifically, the dasher plate 70 lightly grasps the clothes as it is rotated unidirectionally in the clockwise direction, as viewed in Fig. 5, by an angular shearing contact therewith and then 45 quickly discharges the clothes in order that they are moved and rearranged in the substantially circular upstanding path as previously noted. This angular shearing contact with which the clothes are lightly grasped is effected largely by the disposition of the shallow tapered vanes 75, 76 and 77 provided upon the front face of the dasher plate 70; while this quick discharge of the clothes from the front face of the dasher plate 70 is materially facilitated by the shallow recess 50 78 disposed in the front face thereof and positioned between the vanes 76 and 77.

After the clothes have been washed by the machine 10 the user operates the wash switch 120 from its “on” position back into its “off” position in order to interrupt, at the contacts 2 thereof, the circuit for operating the motor 82, and to interrupt, at the contacts 3 thereof, the circuit for energizing the solenoid 84' of the clutch mechanism 84. Also, when the wash switch 120 is returned to its “off” position, there is repre-

pared, at the contacts 1 and 4 thereof, the connections extending between the wash switch 120 and the bag switch 121, whereby the bag switch 121 is again rendered operative to perform its controls. When the motor 82 is thus de-energized, operation thereof is arrested; and when the solenoid 84' is thus de-energized the clutch plates, not shown, of the clutch mechanism 84 are operated into their declutched position. Accordingly, rotation of the rotor of the motor 82 is arrested and the drive connection between the operating shaft 83 and the stub shaft 86 is de-clutched by the clutch mechanism 84 in order to prevent further rotation of the dasher plate 70 unidirectionally in the counterclockwise direction, as viewed from the front of the machine 10.

At this time the clothes contained in the compartment 61 formed in the tub 12 have been washed, and in order to cause the machine 10 to extract the wash liquid therefrom, the user merely operates the bag switch 121 from its "hold" position into its "expand" position. When the bag switch 121 is thus operated into its "expand" position, there is completed, at the contacts 4' thereof, a circuit for operating the motor 82, this circuit including the contacts 1 of the wash switch 120, the conductor 122, the conductor 123 and the contacts 4 of the wash switch 120. Also, when the bag switch 121 is thus operated, into its "expand" position there is completed, at the contacts 5' thereof, a circuit for energizing the solenoids SV1, SV2 and SV3, this circuit including the contacts 1 of the wash switch 120, the conductor 122 and the contacts 4' of the bag switch 121. Finally, when the bag switch 121 is thus operated into its "expand" position, there is completed, at the contacts 6' thereof, a circuit for energizing the solenoids 85' of the clutch mechanism 85, this circuit including the contacts 1 of the wash switch 120, the conductor 122 and the contacts 4' and 5' of the bag switch 121. Accordingly, operation of the motor 82 is again initiated; and when the solenoid 85' is thus energized the clutch plates, not shown, of the clutch mechanism 85 are moved into clutched position, whereby the operating shaft 83 rotates the stub shaft 93 in the counterclockwise direction, as viewed from the front of the machine 10. The valves V1 to V5, inclusive, are normally biased into closed positions, and when the respective solenoids SV1, SV2 and SV3 of the valves V1, V2 and V3 are thus energized, these valves are respectively operated into their open positions. At this time the rotating stub shaft 93 effects rotation of the rotor of the drain pump 98 and the drain valve V1 occupies its open position, whereby the wash liquid contained in the tub 12 is drained therefrom through the drain connection 67, the drain valve V1 and the hose 105 into the inlet connection 104 of the drain pump 98. The operating drain pump 98 discharges the wash liquid through the outlet connection 106 and the outlet conduit 101 to the exterior. Accordingly, the wash liquid contained in the compartment 61 formed in the tub 12 is drained therefrom and is discharged by the drain pump 98 to the exterior.

Also, at this time the rotating stub shaft 93 drives the stub shaft 94 through the fluid drive or coupling mechanism 96, which mechanism 96 accommodates slippage between the stub shafts 93 and 94 for a purpose more fully explained hereinafter. Accordingly, the rotor of the compression pump 99 is rotated in the counterclockwise direction, as viewed from the front of the ma-

chine 10, causing liquid to be supplied via the inlet conduit 100, the open valve V3 and the conduit 108 into the inlet connection 107 of the compression pump 99. The liquid is discharged from the compression pump 99 through the outlet connection 109, the conduit 110, the open valve V2, the conduit 111 and the fixture 112 into the chamber 62. Thus liquid under pressure is supplied into the chamber 62 between the rear section 21 of the tub 12 and the diaphragm 58, whereby the diaphragm 58 is moved forwardly from its normal concave position into its operated convex position. In its convex position the diaphragm 58 substantially conforms to the inner surface of the front section 20 of the tub 12 pressing against the inner sheet 52 of the door 51 and exerting a squeezing action upon the clothes contained in the compartment 61. More particularly, the clothes contained in the compartment 61 are squeezed between the diaphragm 58 and the plate 63 and the dasher plate 70, whereby the absorbed wash liquid is expressed therefrom into the space 66 and falls into the drain connection 67 so that it may be removed to the exterior by the drain pump 98. When a predetermined pressure is exerted upon the diaphragm 58 by the liquid under pressure in the chamber 62, the load upon the compression pump 99 is increased to such an extent that the fluid drive or coupling mechanism 96 causes considerable slippage between the stub shafts 93 and 94. This arrangement limits the pressure that the compression pump 99 may exert upon the liquid in the chamber 62 and consequently the squeezing action that may be exerted by the diaphragm 58 upon the clothes in the compartment 61 of the tub 12. At this time the door 51 is restrained in its closed position by the associated latch mechanism 55 and notwithstanding the pressure exerted thereupon by the diaphragm 58. Also, at this time, the pressure of the liquid in the conduit 111 effects movement of the pressure responsive limit switch LS into its open position, whereby there is interrupted a further point in the circuit for energizing the solenoid 84' of the clutch mechanism 84 in order positively to prevent operation of the clutch mechanism 84 into its clutched position and the consequent rotation of the dasher plate 70 at this time. This arrangement is very advantageous as it positively prevents operation of the dasher plate 70 should the wash switch 120 be inadvertently operated from its "off" into its "on" position at this time while liquid under pressure is contained in the chamber 62 and the clothes in the compartment 61 are undergoing the squeezing action above described.

After the movement of the diaphragm 58 from its concave position into its convex position has been completed and the ultimate pressure exerted by the diaphragm 58 upon the clothes has been brought about by slippage of the fluid drive or coupling mechanism 96 as explained above, the bag switch 121 may be operated from its "expand" position into its "hold" position. When the bag switch 121 is thus returned to its "hold" position, there is interrupted, at the contacts 4' thereof, the previously traced circuit for operating the motor 82; there is interrupted, at the contacts 5' thereof, the previously traced multiple circuits for energizing the solenoids SV1, SV2 and SV3; and there is interrupted, at the contact 6' thereof, the circuit for energizing the solenoids 85' of the clutch mechanism 85. Thus, at this time, operation of the motor 82 is arrested,

and the clutch plates, not shown, of the clutch mechanism 85 are returned to their declutched position in order to prevent further rotation of the stub shafts 93 and 94 by the operating shaft 83. Further, when the solenoids SV1, SV2 and SV3, are thus de-energized the respective valves V1, V2 and V3 are returned to their closed positions. At this time, the pressure that is exerted by the diaphragm 58 upon the clothes in the compartment 61 may be held for any suitable length of time merely by retaining the bag switch 121 in its "hold" position, since the liquid under pressure contained in the chamber 62 is trapped therein as a consequence of the closed positions of the valves V2 and V4.

At any time after the water extracting operation has been performed in the machine 10 the user may relieve the pressure upon the clothes contained in the compartment 61 by operating the bag switch 121 from its "hold" position into its "contract" position. When the bag switch 121 is thus operated, there is completed, at the contacts 3' thereof, a circuit substantially identical to that previously traced for operating the motor 82; there is completed, at the contacts 2' thereof, a circuit similar to that previously traced for energizing the solenoids SV4 and SV5; and there is completed, at the contacts 1' thereof, a circuit substantially identical to that previously traced for energizing the solenoid 85'. Thus, operation of the motor 82 is again initiated, and the clutch mechanism 85 is operated into its clutched position effecting rotation of the stub shafts 93 and 94 in the counterclockwise direction, as viewed from the front of the machine 10. Again the drain pump 98 removes to the exterior any small amount of wash liquid that may have accumulated in the hose 105; and again the compression pump 99 is operated. Specifically, the compression pump 99 draws the liquid contained in the chamber 62 through the fixture 112, the conduit 111, the open valve V4 and the conduit 108 into the inlet fixture 107 and then discharges the liquid therefrom through the outlet fixture 109 and the open valve V5 into the outlet conduit 101 and thence to the exterior. At this time, the valves V4 and V5 occupy their open positions as a consequence of the energization of the respective solenoids SV4 and SV5. Accordingly, as the liquid in the chamber 62 formed in the tub 12 is discharged to the exterior the diaphragm 58 is moved from its convex position back into its concave position, air entering the compartment 61, as the diaphragm 58 is thus moved, through the opening 49, since the door 51 in its closed position is not sealed in gas-tight relation with the opening 49. When the diaphragm 58 is completely returned to its normal concave position all of the liquid in the chamber 62 has been withdrawn therefrom and the pressure in the conduit 111 is relieved, whereby the pressure responsive limit switch LS is again operated to close the associated contacts included in the previously traced circuit for energizing the solenoid 84' of the clutch mechanism 84 in order again to render operative the wash switch 120 to control the operation of the dasher plate 70.

At this time, the bag switch 121 may be returned from its "contract" position into its "hold" position. When the bag switch 121 is thus operated back into its "hold" position, there is interrupted, at the contacts 3' thereof, the circuit for operating the motor 82; there is interrupted, at the contacts 2' thereof, the multiple circuits for energizing the solenoids SV4 and SV5; and there

is interrupted, at the contacts 1' thereof, the circuit for energizing the solenoid 85'. At this time, operation of the motor 82 is arrested, and the clutch mechanism 85 is returned into its declutched position. Also, the valves V4 and V5 are respectively returned to their closed positions.

In view of the foregoing, it will be understood that the circuit interlock arrangement, including the limit switch LS, positively prevents operation of the dasher plate 70 when the clothes in the compartment 61 in the tub 12 are under compression between the diaphragm 58 and the plate 63 and the dasher 70, thereby positively preventing any possible damage to the clothes in the event of inadvertent operation of the wash switch 120 from its "off" position into its "on" position at this time. Moreover, the interlock connections, including the conductors 122 and 123, between the wash switch 120 and the bag switch 121 positively prevent expansion or contraction of the diaphragm 58 as a result of inadvertent operation of the bag switch 121 while the wash switch 120 occupies its "on" position.

After the wash liquid has thus been extracted from the clothes, a rinsing operation may be obtained by the user after opening the door 51 and the introduction of rinse water or liquid into the compartment 61. Specifically, at this time, the user repeats the wash operation, without the addition of detergent, for any suitable length of time; and then repeats the liquid extracting operation in order to insure that all of the rinse liquid is expressed from the clothes contained in the compartment 61. Thereafter the diaphragm 58 is again returned its concave position; and at this time the door 51 may be moved into its open position and the clothes may be removed from the compartment 61 through the opening 49 after the washing and rinsing operations have been performed as explained above.

In view of the foregoing it will be understood that in the machine 10, the tub 12, the supporting plate 39, and all of the operating elements carried thereby, with the exception of the V-belt 90, comprise a subassembly that may be readily placed and removed with respect to the open top of the base 11. More specifically, the subassembly noted, is completed; and then the operating elements carried by the supporting plate 39 are inserted into the open top of the base 11 and lowered into place. When the tub 12 is lowered into its final position the opposite ends of the supporting plate 39 engage the flanges provided on the substantially L-shaped members 40 and 41, the bearing hangers 87 and 95 respectively projecting through aligned openings provided in the respective flanges of the members 40 and 41. As the tub 12, the supporting plate 39 and the elements carried by the supporting plate 39, are lowered into place in the base 11, the pulley 88 is projected through the opening 89 formed in the front wall 13 and the inlet and outlet conduits 100 and 101 are projected through an opening 131 formed in the rear wall 14. At this time, the front end of the operating shaft 71 overhangs the upper edge of the front wall 13 and the front end of the stub shaft 86 projects through the opening 89 formed in the front wall 13. Moreover, the pulleys 88 and 74 are disposed forwardly with respect to the front wall 13, whereby the V-belt 90 may then be placed upon the pulleys 74 and 88 forwardly of the front wall 13 without interference therewith. Then the control wires extending to the operating motor 82, the limit switch LS, the clutch solenoids 84' and

85' and the valve solenoids SV1 to SV5, inclusive, are extended through the opening 89 formed in the front wall 13 as required and are connected to the corresponding control wires arranged in the hood 91 and extending to the switches 120 and 121. The control wires arranged in the hood 91 and extending to the switches 120 and 121 are suitably secured in place therein in order to prevent them from contacting the V-belt 90. At this time, the lower end of the hood 91 is disposed closely adjacent to the lower portion of the front wall 13 near the opening 89 formed therein, whereupon the hood 91 is pivoted rearwardly into place against the front wall 13 of the base 11 and the front wall 25 of the tub 12. Ultimately, the hood 91 is secured in place employing the screws 92 extending into the tapped holes provided in the stanchions 65.

In view of the foregoing, it will be understood that the hood 91 is readily removable in order to permit adjustment of the V-belt 90 and access to the pulleys 74 and 88. Moreover, it will be appreciated that after the hood 91 has been removed the V-belt 90 may be removed and the electrical wiring may be disconnected in order to permit complete removal from the base 11 of the subassembly comprising the tub 12, the supporting plate 39 and the operating elements mentioned that are carried thereby. This arrangement is very advantageous as the subassembly may be readily removed from the base 11 for purposes of inspection and repair, if necessary.

A modified form of the diaphragm or bag 200 that is incorporated in the machine 210, and embodying the features of the present invention, is illustrated in Fig. 7. Specifically, this modified form of the bag 200 is of unitary double-wall molded construction including substantially cup-shaped inner and outer walls 201 and 202 normally arranged in concave nested relation. The outer wall 202 is provided with a configuration substantially conforming to that of the inner surface of the rear section 221 of the tub 212; and the inner wall 201 is arranged in nested relation with the outer wall 202 as previously noted defining a chamber 262 therebetween. In this embodiment of the bag 200 the marginal edges of the walls 201 and 202 may be molded or vulcanized together to provide a junction as indicated at 203, whereby the bag 200 is of unitary construction. The material of the bag 200 may be formed of rubber, or the like, and the marginal junction 203 thereof is clamped between the inner and outer rings 223 and 224 of the tub 212 in a manner similar to that previously described in conjunction with the diaphragm 58 incorporated in the machine 10.

In this arrangement the fixture 312 that communicates with the associated conduit 311 that is carried by the bottom wall 228 communicates directly with the chamber 262 formed between the walls 201 and 202. Moreover, in this arrangement the outer wall 202 may be cemented or otherwise directly secured to the adjacent inner surface of the rear section 221 of the tub 212.

The operation of this modified form of the bag 200 is substantially identical to that of the diaphragm 58 incorporated in the machine 10 except that in this case the outer wall 202 is stationary and the inner wall 201 is movable between a normal concave position and an operated convex position, the liquid under pressure being supplied directly into the chamber or void 262 formed between the walls 201 and 202 of the bag 200.

This embodiment of the bag 200 has certain advantages in that the liquid is contained entirely within the bag 200 rendering it unnecessary that the rear section 221 of the tub 212 be of imperforate construction. In other words, the rear section 221 of the tub 212 merely supports the outer wall 202 of the bag 200 and forms no part of the liquid containing chamber 262.

In view of the foregoing it is apparent that there has been provided a portable clothes washing machine that is especially suitable for use in apartments, or the like; which machine is of rugged and economical construction and arrangement, and that embodies both washing and liquid extracting facilities, and is efficient in operation, and is of attractive appearance and design.

While there has been described what is at present considered to be the preferred embodiment of the invention, it will be understood that various modifications may be made therein, and it is intended to cover in the appended claims all such modifications as fall within the true spirit and scope of the invention.

25 What is claimed is:

1. A clothes washing machine comprising a stationary tub including a pair of opposed vertically disposed end walls and a horizontally disposed connecting tubular side wall, a vertically disposed flexible diaphragm arranged in said tub and secured about the perimeter thereof to an intermediate portion of said side wall, said diaphragm being movable in a horizontal direction from a concave position disposed adjacent to one end of said side wall and one of said end walls to a convex position disposed adjacent to the other end of said side wall and the other of said end walls, said diaphragm in its concave position cooperating with said other end of said side wall and said other end wall to define a compartment therebetween adapted to contain clothes and wash liquid, said other end of said side wall having an opening formed in the upper portion thereof above the level of the wash liquid contained in said compartment and rendering said compartment accessible from the exterior, a door mounted for movements between open and closed positions with respect to said opening, a vertically disposed substantially disk-like dasher arranged in said compartment in a submerged position with respect to the wash liquid contained therein and adjacent to said other end wall and mounted thereon for rotation in order to produce a washing action upon the clothes in said compartment, means for draining wash liquid from said compartment during movement of said diaphragm from its concave position into its convex position to produce a squeezing action upon the clothes in said compartment between said diaphragm and said dasher in order to express the wash liquid therefrom, and means for moving said diaphragm from its concave position into its convex position.

2. A clothes washing machine comprising a stationary tub including a pair of opposed vertically disposed end walls and a horizontally disposed connecting tubular side wall, a vertically disposed flexible diaphragm arranged in said tub and secured about the perimeter thereof to an intermediate portion of said side wall, said diaphragm being movable in a horizontal direction from a concave position disposed adjacent to one end of said side wall and one of said end walls to a convex position disposed adjacent to

the other end of said side wall and the other of said end walls, said diaphragm in its concave position cooperating with said other end of said side wall and said other end wall to define a compartment therebetween adapted to contain clothes and wash liquid, said other end of said side wall having an opening formed in the upper portion thereof above the level of the wash liquid contained in said compartment and rendering said compartment accessible from the exterior, a door mounted for movements between open and closed positions with respect to said opening, a vertically disposed perforated wall arranged in said compartment adjacent to said other end wall and in spaced relation with respect thereto, a vertically disposed substantially disk-like dasher arranged in said compartment in a submerged position with respect to the wash liquid contained therein and adjacent to said perforated wall and mounted upon said other end wall for rotation in order to produce a washing action upon the clothes in said compartment, means for draining wash liquid from said compartment during movement of said diaphragm from its concave position into its convex position to produce a squeezing action upon the clothes in said compartment between said diaphragm and said perforated wall and said dasher in order to express the wash liquid from the clothes, and means for moving said diaphragm from its concave position into its convex position.

3. A clothes washing machine comprising a stationary tub including front and rear substantially cup-shaped sections disposed in facing relation and respectively providing front and rear vertically disposed end walls and horizontally disposed connecting front and rear side walls, said front and rear end walls being arranged in opposed relation and the ends of said front and rear side walls being arranged adjacent to each other, a vertically disposed flexible diaphragm arranged in said tub, the perimeter of said diaphragm being disposed adjacent to the ends of said front and rear side walls, a vertically disposed ring arranged in said tub adjacent to the ends of said front and rear side walls, means including said ring for joining the ends of said front and rear side walls together in liquid-tight relation and for clamping the perimeter of said diaphragm to the joint between the ends of said front and rear side walls in fluid-tight relation, said diaphragm being movable in a horizontal direction from a concave position disposed adjacent to said rear side wall and said rear end wall to a convex position disposed adjacent to said front side wall and said front end wall, said diaphragm in its concave position cooperating with said front side wall and said front end wall to define a compartment therebetween adapted to contain clothes and wash liquid, said front side wall having an opening formed in the upper portion thereof above the level of the wash liquid contained in said compartment and rendering said compartment accessible from the exterior, a door mounted for movements between open and closed positions with respect to said opening, a vertically disposed substantially disk-like dasher arranged in said compartment in a submerged position with respect to the wash liquid contained therein and adjacent to said front end wall and mounted thereon for rotation in order to produce a washing action upon the clothes in said compartment, means for draining wash liquid from said compartment during movement of said diaphragm from its concave position into

its convex position to produce a squeezing action upon the clothes in said compartment between said diaphragm and said dasher in order to express the wash liquid therefrom, said diaphragm in its concave position cooperating with said rear side wall and said rear end wall to define a chamber therebetween adapted to receive a fluid under pressure in order to move said diaphragm from its concave position into its convex position, and means for supplying fluid under pressure into said chamber.

4. A clothes washing machine comprising a stationary tub including a pair of opposed vertically disposed end walls and a horizontally disposed connecting tubular side wall, a vertically disposed hollow bag arranged in said tub and including an outer wall supported by one end of said side wall and one of said end walls and a flexible inner wall or diaphragm movable in a horizontal direction between concave and convex positions with respect to said outer wall, said diaphragm in its concave position cooperating with said other end of said side wall and said other end wall to define a compartment therebetween adapted to contain clothes and wash liquid, said other end of said side wall having an opening formed in the upper portion thereof above the level of the wash liquid contained in said compartment and rendering said compartment accessible from the exterior, a door mounted for movements between open and closed positions with respect to said opening, a vertically disposed substantially disk-like dasher arranged in said compartment in a submerged position with respect to the wash liquid contained therein and adjacent to said other end wall and mounted thereon for rotation in order to produce a washing action upon the clothes in said compartment, means for draining wash liquid from said compartment during movement of said diaphragm from its concave position into its convex position to produce a squeezing action upon the clothes between said diaphragm and said dasher in said compartment in order to express the wash liquid therefrom, and a fitting communicating with the interior of said bag to accommodate the supply of a fluid under pressure thereto in order to move said diaphragm from its concave position into its convex position.

5. The clothes washing machine set forth in claim 4, wherein said hollow bag is of unitary molded construction and formed of rubber, or the like.
